VALVE

John W. Marsh, Alexandria, Va.

Application May 30, 1945, Serial No. 596,637

14 Claims. (Cl. 303—55)

1

This invention relates to new and useful improvements in valves, and has for an object the provision of a valve which will maintain any desired pressure on the discharge side. Another object of the invention is the provision of a valve having a large orifice for the rapid accumulation of pressure on the discharge side with prompt and positive closure when desired pressure is reached. A further object of the invention is to provide a valve having accurate control of released pressure without manipulation of the control handle between discharge and lap positions. Yet another object of this invention is to provide a valve structure of the type described which is provided with poppet valves which are substantially balanced for accurate control. A still further object of the invention is to provide a pressure control valve which is simple and easy to construct and requires a minimum of maintenance. Still another object of the invention is to provide a fluid pressure system embodying as a part thereof a novel valve of the type just described.

A valve embodying the present invention may be used in all cases wherein it is desired to maintain a predetermined fluid pressure, and it is particularly adaptable for the control of train-line pressure in an air-brake system. The valve commonly used for this purpose consists of a rotatable disc on a flat seat, the disc and seat being provided with ports. Provision is made for registration of ports communicating with a source of fluid pressure and the train line, as well as with an equalizing chamber, to charge the train line and the equalizing chamber. Other ports provide communication between a source of fluid pressure and a pressure-reducing valve, and between the pressure-reducing valve and the train line and the equalizing chamber to maintain operating pressure in the train line and the equalizing chamber. Other ports provide communication between the equalizing chamber and the atmosphere to reduce pressure in the equalizing chamber. Yet other ports provide communication between the train line and the atmosphere for emergency brake applications. Service reductions in train-line pressure are attained by reducing pressure in the equalizing chamber above an equalizing piston, the underside of which is subject to train-line pressure. Train-line pressure then raises the equalizing piston which opens a valve venting the train line to atmosphere until the pressure under the equalizing piston is reduced sufficiently to permit the reduced equalizing chamber pressure to move the equalizing piston down and close the venting valve. It is also

2

a common practice to provide a lap position of the valve to close all ports and hold pressures attained.

It will be observed that the presently used valving system only charges or releases pressure from a system just as the manual opening or closing of a plurality of valves having similar communications would do. No provision is made for the maintenance of a predetermined fluid pressure without further attention on the part of the operator. Fluid pressure in a communicating or utilizing means may be decreased or increased, such as by movement of a piston in the utilizing means, by leakage, or by the effect of temperature changes, condensation or evaporation. The present invention compensates for any changes in a predetermined fluid pressure, and automatically maintains such pressure on the discharge side of the valve, corresponding to the valve setting.

Since the valve of the present invention will automatically maintain a predetermined pressure on the discharge side, the entire operation of an air-brake system becomes greatly simplified. It may be taught to a beginner in a much shorter time than is now required, and the operation of the entire system is more positive and under better over-all control. It also eliminates the need for an equalizing reservoir and a feed valve.

A valve embodying the principles of the present invention, while extremely useful in air-brake applications, will have a large variety of other uses as well, all as will be appreciated by those skilled in the art.

In the drawing:

Fig. 1 is a vertical section taken through a valve embodying the present invention.

Fig. 2 is a horizontal section taken on line 2—2 of Fig. 1.

The self-lapping, automatic brake valve utilizing a floating seat principle, and combining the functions of the conventional automatic brake valve, equalizing reservoir, and feed valve, is illustrated in Figs. 1 and 2. This valve includes a housing which may be formed in a plurality of sections 10, 11, 12 and 13. By forming the housing in this fashion, the valve is readily assembled, the sections having aligned apertures 14 in the several corner sections 15 which receive bolts 50 (not shown) for assembly. Chamber 19 communicates with port 20, which may be considered as the outlet port, leading to the train line, and control chamber 21 communicates with exhaust port 22 leading to the external atmosphere in a manner later to be described. The housing

further includes port 23, which may be considered as the inlet port, connecting the main reservoir with chamber 24.

At 26 there is illustrated a double-seated valve comprising lower valve portion 27 seated at 28, which is a fixed seat, and an upper valve portion 29 which is seated at 30, which is a floating seat associated with a pressure actuated member, such as a piston 31 which moves in a piston chamber 33 formed intermediate the upper and lower ends of upper housing section 13. Valve 26 is mounted for reciprocating movement in valve support 32 formed in upper housing section 13. This valve structure is formed with a recess 34 to permit air to pass from chamber 24 connected with the main reservoir to chamber 21 when lower valve portion 27 is open. A relatively heavy spring 38 urges piston 31 downwardly, thus closing valve portion 29. Pressure of spring 38 is controlled by a handle 39 which operates a sharp-pitched screw 40, the handle being keyed to the screw by any suitable means, such as by pin 43. A spring cap 41 engages the upper end of spring 38, and a ball 42 may be positioned between the spring cap and screw 40. The ball provides a friction-free seat. It takes up any cocking of the spring, and centers the load on the spring in order to permit the spring to float freely so as to avoid cocking the piston. When upper valve portion 29 is open, air in chamber 21 may be vented through seat 30, through port 22, and to the external atmosphere.

A fluid pressure actuated member, such as a piston 46 mounted in piston chamber 47 is subject on its lower surface to pressure in chamber 21. Piston 46 forms a floating seat 48 for lower valve portion 49 of a double-seated valve 50. The upper valve portion 51 of this double-seated valve is seated at 52, which is a fixed seat. Valve 50, which may be similar in construction to valve 26, is mounted for reciprocating movement in valve support 53. With handle 39 in running position, i. e., the full normal tension of spring 38 urging piston 31 downwardly to the position of Fig. 1, valves 27—29 are closed. The spring is so tensioned as to close seats 28 and 30 when normal train-line pressure exists in chamber 21.

Any pressure in chamber 21 in excess of pressure in train-line chamber 19, due to reduction in train-line pressure, raises piston 46, closing valve 49 and opening valve 51, thereby admitting main reservoir air directly to the train line. When the train-line pressure equalizes with the controlled pressure in chamber 21, piston 46 moves downwardly to close valve 51. This valve permits full flow of main reservoir air to the train line for rapid charging of the brake system right up to equalization pressure. The train line could, of course, be charged direct from chamber 21, but as the train-line pressure approached control pressure, valve 27 would close gradually, extending the time of charging and causing excessive wear on the seat by wire drawing. When pressure is reduced in chamber 21 by opening handle 39, piston 46 is pushed down by the excessive train-line pressure, exhausting train-line air through valve 49 to chamber 21, and out through valve 29 and port 22. A restricted port 54 may be provided in piston 46, forming means for communication between chambers 19 and 21. Port 54 may be of appropriate size to maintain train-line pressure against normal leakage, and to maintain equalization of pressure between chambers 19 and 21, except when a substantial pressure change is effected in chamber 21 by operation of handle 39. The effect of

restricted port 54 is to prevent too violent action of piston 46 which may result in undesirable pressure waves in the train line which communicates with chamber 19. Relatively small spring 59 which urges valve member 50 upwardly, and small spring 56 which urges valve member 26 downwardly, serve to balance the main reservoir pressure on valves 26 and 50.

The admission or discharge of fluid from chamber 19 to increase or decrease fluid pressure in chamber 19 is effected by movement of piston 46, the upper surface of which is subjected to fluid pressure in chamber 19. The lower surface of piston 46 is subjected to fluid pressure in chamber 21, and an increase of fluid pressure in chamber 21 and below piston 46, over the fluid pressure in chamber 19, will move piston 46 upwardly, closing valve 49 and opening valve 51, thereby admitting fluid from chamber 24 to chamber 19 until fluid pressure in chamber 19 and above piston 46 overcomes the fluid pressure in chamber 21 and below piston 46, whereupon piston 46 is forced downwardly, permitting valve 51 to close.

The self-lapping valve of the present invention automatically keeps train-line pressure equal to spring pressure. When the downward pressure on piston 31 exceeds the fluid pressure in chamber 21, which latter pressure acts on the lower surface of piston 31, piston 31 is forced downwardly, opening valve 27 and permitting fluid to flow from chamber 24 to chamber 21. This flow continues until fluid pressure in chamber 21 and below piston 31 is sufficient to raise piston 31 against downward pressure of spring 38 until valve 27 is closed. Similarly, when the downward spring pressure on piston 31 is less than the fluid pressure in chamber 21 which acts on the lower surface of piston 31, piston 31 is forced upwardly and away from valve 29, thereby permitting fluid to flow from chamber 21, past valve seat 30, and to escape through port 22.

A reduction of fluid pressure in chamber 21 and below piston 46, below the fluid pressure in chamber 19, will move piston 46 downwardly, opening valve 49 and permitting fluid in chamber 19 to flow to chamber 21, thereby increasing fluid pressure in chamber 21, raising piston 31 away from valve 29, and permitting fluid to escape as aforesaid. Such reduction of fluid pressure in chamber 21 will cause full downward movement of piston 46, thereby causing a rapid rise in fluid pressure in chamber 21 and immediate rapid raising of piston 31 and discharge of fluid from chamber 19. An increase of fluid pressure in chamber 21 and below piston 46, above the fluid pressure in chamber 19, causes full upward travel of piston 46, full opening of valve 51, and direct communication between a source of fluid pressure at opening 23 and chamber 19, until fluid pressure in chamber 19 and above piston 46 is raised sufficiently to move piston 46 downwardly against fluid pressure established in chamber 21, and promptly close valve 51 against further flow of fluid from chamber 24.

Maximum pressure on spring 38 is applied to piston 31 when in running position. When a brake application is made, handle 39 is moved, thus reducing spring pressure on piston 31, permitting upward travel thereof due to train-line pressure in the control chamber. This opens seat 30 and exhausts control pressure through exhaust port 22. Pressure in chamber 19, being in excess of pressure in chamber 21, moves piston 46 downwardly, thus venting train-line pressure into chamber 21. This increase in pressure in chamber 21, acting against reduced spring pressure,

permits train-line air to exhaust until train-line pressure equalizes with reduced spring pressure. Valve seats 52 and 28 remain closed, of course, during reduction.

Release of brakes is effected by return of handle 39 to running position. The reduced pressure in control chamber 21 required for brake application is insufficient to oppose downward movement of piston 31 which is now actuated by full spring pressure. The excess of spring pressure causes double-seated valve 26 to move downwardly, opening seat 27 and admitting reservoir air into control chamber 21 until pressure therein equals spring pressure, which, for instance, may be 70 pounds. Pressure in chamber 19 is still reduced, and the pressure in chamber 21, being higher, acts against the undersurface of piston 46, moving it upwardly, closing floating seat 48 and opening fixed seat 52 of valve 50. Since seat 52 is now full open, reservoir air travels into chamber 19 and the train line. When pressures in chambers 19 and 21 equalize, piston 46 moves down and closes seat 52. The valves are now in lap position.

It will be apparent that any movement of handle 39 will effect a change in the downward pressure of spring 38, and that such pressure change will be reflected in chamber 21 and in chamber 19. Thus, pressure in any means communicating with chamber 19 can be graduated up or down at the will of the operator by setting handle 39 in the corresponding position, and the desired pressure will be maintained at the means communicating with chamber 19 up to the limit of the source of fluid pressure at inlet 23.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles thereof.

What I claim is:

1. In a fluid pressure control valve, the combination of a housing having an inlet port, an outlet port, an exhaust port, and a control chamber, a double-seated valve provided with a first seat forming a closure between said inlet and outlet ports, a second seat forming a closure between the outlet port and the control chamber, a fluid pressure actuated element positioned between said outlet port and said control chamber for controlling movement of the double-seated valve, the housing having an opening between the inlet port and the control chamber, and a manually controllable valve for closing such opening and for exhausting fluid from the control chamber.

2. In a fluid pressure control valve, the combination of a housing having an inlet port, an outlet port, and a control chamber, a double-seated valve provided with a first valve member forming a closure between said inlet and outlet ports, a second valve member forming a closure between the outlet port and the control chamber, a fluid pressure actuated element positioned between said outlet port and said control chamber for controlling movement of the double-seated valve, means for controlling fluid pressure in said control chamber, said means comprising a valve having a seat providing an opening between the

inlet port and the control chamber, and manually controllable means for opening said latter valve.

3. In a fluid pressure control valve, the combination of a housing having an inlet port, an outlet port, an exhaust port, and a control chamber, a double-seated valve provided with a first valve member forming a closure between said inlet and outlet ports, a second valve member forming a closure between the outlet port and the control chamber, a fluid pressure actuated element positioned between said outlet port and said control chamber for controlling movement of the double-seated valve, and means for controlling fluid pressure in said control chamber, said means comprising a second fluid pressure actuated element positioned between said control chamber and said exhaust port and being provided with a valve seat communicating with said exhaust port, one surface of said second fluid pressure actuated element being subject to fluid pressure in said control chamber, a second double-seated valve provided with a first valve member forming a closure between said inlet port and said control chamber, a second valve member adapted to engage said valve seat on said latter fluid pressure actuated element, and resilient compressible means engaging said fluid pressure actuated element to oppose movement thereof due to fluid pressure in said control chamber.

4. In a fluid pressure control valve, the combination of a housing having an inlet port, an outlet port, a control chamber, and an exhaust port, a fluid pressure actuated element positioned between said control chamber and said exhaust port and being provided with a valve seat communicating with said exhaust port, one surface of said fluid pressure actuated element being subject to fluid pressure in said control chamber, a double-seated valve provided with a first valve member forming a closure between said inlet and outlet ports, and a second valve member adapted to engage said valve seat on said fluid pressure actuated element, resilient compressible means engaging said fluid pressure actuated element to oppose movement thereof due to fluid pressure in said control chamber, a second double-seated valve provided with a first valve member forming a closure between said inlet and outlet ports, and a second valve member forming a closure between the outlet port and the control chamber, a second fluid pressure actuated element positioned between said outlet port and said control chamber for controlling movement of the latter valve, said latter fluid pressure actuated element having an opening therein providing a floating seat for the second valve member of the second double-seated valve.

5. In a fluid pressure control valve, the combination of a housing having an inlet chamber, an outlet chamber, a control chamber, and an opening between said inlet and outlet chambers, a valve adapted to close said opening, a fluid pressure actuated element positioned between said outlet chamber and said control chamber and subject to fluid pressure in each said chamber, said fluid pressure actuated element being adapted to actuate said valve, and a restricted port between said outlet chamber and said control chamber.

6. In a fluid pressure control valve, the combination of a housing provided with an inlet chamber, an outlet chamber, and means to effect unrestricted opening therebetween, said means

comprising a valve element positioned between said inlet and outlet chambers, fluid pressure actuated means for actuating said valve element, such fluid pressure actuated means being subject to fluid pressure in said outlet chamber on one side thereof and subject to controlled fluid pressure on its opposite side, whereby said valve element is full open when said controlled fluid pressure exceeds said outlet chamber fluid pressure, and whereby said valve element is full closed when said outlet chamber fluid pressure is not less than said controlled fluid pressure, and self-lapping means for controlling said latter fluid pressure.

7. In a fluid pressure control valve, the combination of a housing provided with an inlet chamber, an outlet chamber, means to effect an unrestricted opening therebetween, and means to effect a restricted opening therebetween, said former means comprising a valve element positioned between said inlet and outlet chambers, fluid pressure actuated means for actuating said valve element, such fluid pressure actuated means having two opposite surfaces of substantially equal areas and being subject to fluid pressure in said outlet chamber over one such entire surface, and subject to controlled fluid pressure over the second entire surface, whereby said valve element is full open when said controlled fluid pressure substantially exceeds said outlet chamber fluid pressure, and whereby said valve element is full closed when said outlet chamber fluid pressure is not less than said controlled fluid pressure, and means for controlling said latter fluid pressure

8. In a fluid pressure control valve, the combination of a housing provided with an inlet chamber, an outlet chamber, means to effect unrestricted opening therebetween, said means comprising a valve element positioned between said inlet and outlet chambers, fluid pressure actuated means to actuate said valve element, said fluid pressure actuated means having two opposite surfaces of substantially equal areas and being subject to fluid pressure in said outlet chamber over one such entire surface, and subject to controlled fluid pressure over the second entire surface, whereby said valve element is full open when said controlled fluid pressure exceeds said outlet chamber fluid pressure, and whereby said valve element is full closed when said outlet chamber pressure is not less than said controlled fluid pressure, said latter fluid pressure being controlled by self-lapping means comprising a double-seated valve having a first seat adapted to provide communication between said inlet chamber and controlled fluid pressure side of aforesaid fluid pressure actuated means, and a second seat adapted to provide communication between controlled fluid pressure side of aforesaid fluid pressure actuated means and exhaust, a second fluid pressure actuated means to actuate said double-seated valve, such latter second fluid pressure actuated means being subject to said controlled fluid pressure on one side thereof and subject to controllable, resiliently compressible means on its opposite side.

9. In a fluid pressure control valve, the combination of a housing having an inlet chamber, an outlet chamber and a control chamber, means to effect unrestricted opening between said inlet and outlet chambers, said means comprising a valve element positioned between said inlet and outlet chambers, fluid pressure actuated means to actuate said valve element, such fluid pressure actuated means having two opposite surfaces of

substantially equal areas and being subject to fluid pressure in said outlet chamber over one such entire surface, and subject to controlled fluid pressure over the second entire surface, whereby said valve element is full open when said control chamber fluid pressure substantially exceeds said outlet chamber fluid pressure, and whereby said valve element is full closed when said outlet chamber fluid pressure is substantially not less than said control chamber fluid pressure, a restricted port between said control chamber and said outlet chamber, and self-lapping means for controlling fluid pressure in said control chamber.

15 10. In a fluid pressure control valve, the combination of a housing having an inlet chamber, an outlet chamber, and a control chamber, means to effect unrestricted opening between said inlet and outlet chambers, said means comprising a
20 valve element positioned between said inlet and outlet chambers, fluid pressure actuated means to actuate said valve element, said fluid pressure actuated means having two opposite surfaces of substantially equal areas and being subject to
25 fluid pressure in said outlet chamber over one such entire surface, and subject to controlled fluid pressure over the second entire surface, whereby said valve element is full open when said control chamber fluid pressure exceeds said outlet chamber fluid pressure, and whereby said valve element is full closed when said outlet chamber fluid pressure is not less than said control chamber fluid pressure, a second valve element associated with the aforesaid valve element
30 and associated with a seat on aforesaid fluid pressure actuated means, whereby said seat is opened by movement of said fluid pressure actuated means when said outlet chamber fluid pressure exceeds said control chamber fluid pressure,
35 thereby establishing communication between said outlet and control chambers, and means for controlling fluid pressure in said control chamber.

11. In a fluid pressure control valve structure, the combination of a housing having an inlet chamber, an outlet chamber, a control chamber, and an exhaust port, means to effect unrestricted opening between said inlet and outlet chambers, said means comprising a valve element positioned between said inlet and outlet chambers, fluid pressure actuated means to actuate said valve element, such fluid pressure actuated means having two opposite surfaces of substantially equal areas and being subject to fluid pressure in said outlet chamber over one such entire surface, and subject to controlled fluid pressure over the second entire surface, whereby said valve element is full open when said control chamber fluid pressure substantially exceeds said outlet chamber fluid pressure, and whereby said valve element is full closed when said outlet chamber fluid pressure is not less than said control chamber fluid pressure, a second valve element associated with aforesaid valve element and associated with a seat on aforesaid fluid pressure actuated means, whereby said seat is opened by movement of said fluid pressure actuated means when said outlet chamber fluid pressure exceeds said control chamber fluid pressure, thereby establishing communication between said outlet and control chambers, means to control fluid pressure in said control chamber, said means comprising a double-seated valve having a first seat controlling communication between said inlet chamber and said control chamber, and a second seat controlling communication between said control chamber

and aforesaid exhaust port, a second fluid pressure actuated means carrying said second seat, said second fluid pressure actuated means having one surface subject to fluid pressure in said control chamber, said fluid pressure being opposed by resiliently controllable means, whereby increase of pressure on said resiliently controllable means opens said first seat to admit fluid under pressure from said inlet chamber to said control chamber, and whereby decrease of pressure on said resiliently controllable means permits said first seat to close and opens said second seat to exhaust fluid under pressure from said control chamber to aforesaid exhaust port.

12. A structure as described in claim 11, with a restricted port between said control chamber and said outlet chamber.

13. In a fluid pressure control valve, the combination of a housing provided with an inlet chamber, an outlet chamber, and means to effect unrestricted opening therebetween, said means comprising a valve element positioned between said inlet and outlet chambers, fluid pressure actuated means for actuating said valve element, such fluid pressure actuated means being subject to fluid pressure in said outlet chamber on one side thereof and subject to controlled fluid pressure on its opposite side, whereby said valve element is full open when said controlled fluid pressure exceeds said outlet chamber fluid pressure, and whereby said valve element is full closed when said outlet chamber fluid pressure is not less than said controlled fluid pressure, and

- means for controlling said latter fluid pressure.
14. In a fluid pressure control valve, the combination of a housing having an inlet chamber, an outlet chamber and a control chamber, means to effect unrestricted opening between said inlet and outlet chambers, said means comprising a valve element positioned between said inlet and outlet chambers, fluid pressure actuated means to actuate said valve element, such fluid pressure actuated means being subject to fluid pressure in said outlet chamber on one side thereof and subject to fluid pressure in said control chamber on its opposite side, whereby said valve element is full open when said control chamber fluid pressure substantially exceeds said outlet chamber fluid pressure, and whereby said valve element is full closed when said outlet chamber fluid pressure is substantially not less than said control chamber fluid pressure, a restricted port between said control chamber and said outlet chamber, and means for controlling fluid pressure in said control chamber.
